UNITED STATES PATENT OFFICE.

EDWIN T. BASKIN, OF INDEPENDENCE, MISSOURI.

GLOVE.

1,072,560.

Specification of Letters Patent.

Patented Sept. 9, 1913.

Application filed July 29, 1912. Serial No. 712,152.

to all whom it may concern:

Be it known that I, EDWIN T. BASKIN, a citizen of the United States, residing at Independence, in the county of Jackson and State of Missouri, have invented a new and useful Glove, of which the following is a specification.

This invention relates to gloves or mittens, and aims to provide a reversible glove, which may be worn either by the right or left hand, the present glove being an improvement over the glove disclosed in my pending application for patent on "mittens", filed Feb. 16, 1912, Serial No. 677,941.

It is a further object of the present invention to provide a reversible glove of novel construction wherein there are as few seams as possible and wherein the seams are located most conveniently, the parts of the glove being capable of being cut from flannel cloth or other material economically, so as to reduce the cost of manufacture.

This invention also contemplates the production of a glove having an inner facing for the index finger and thumb, which also reinforces the quirks.

Another object of this invention is to provide a novel glove wherein the thumb and index finger pockets are integral, or are formed from a single blank in a novel manner.

With the foregoing general objects outlined, the present invention resides in the novel construction and combination of parts hereinafter set forth and particularly claimed, it being understood that this device is susceptible of alterations or deviations in its details within the scope of the appended claims without departing from the spirit of the invention.

The invention has been illustrated in the accompanying drawings, wherein similar reference characters have been employed to denote corresponding parts, and wherein,—

Figure 1 is a side elevation of one form of the glove. Fig. 2 is a plan view of the blank from which the thumb and index finger pockets are constructed. Fig. 3 is a plan view of the blank forming the inner facing for the index finger and thumb pockets. Fig. 4 is a side elevation of a second form of glove. Fig. 5 is a side ele-

vation of a gauntlet glove embodying the present invention. Fig. 6 is a plan view of the blank from which the index finger and thumb pockets of the gauntlet glove are formed. Fig. 7 is a side elevation of a fourth form of glove. Fig. 8 is a plan view of the blank from which the thumb and index finger pockets of the fourth form of glove are formed. Fig. 9 is a side elevation of a fifth form of glove. Fig. 10 is a side elevation, looking in the opposite direction, of the glove shown in Fig. 9. Fig. 11 is a side elevation of a sixth form of glove.

Referring specifically to the drawings, and particularly to the form of glove shown in Fig. 1, the index finger and thumb pockets thereof are constructed of a blank, as illustrated in Fig. 2. This blank is symmetrical at the sides of the median line 1 and has oppositely projecting index finger and thumb sections 2 and 3, respectively, along the median line. The thumb sections 3 are provided with extensions 4, the index finger and thumb sections being separated by cuts or slits 5 terminating short of the median line 1. This blank is doubled or folded on the median line 1 and is bent between the index finger and thumb sections to provide the quirks 6, the extensions 4 of the thumb sections 3 extending downwardly along the edge of the wrist portion of the glove.

An inner facing is secured within the index finger and thumb pockets, the same comprising a blank of elongated form as shown in Fig. 3, this blank being symmetrical at the sides of the median line 7 and has the oppositely projecting finger and thumb portions 8 and 9, respectively, along the median line. This facing blank is doubled or folded on the median line 7 and the median line thereof is made to coincide with the median line of the former blank, as shown in dot and dash lines in Fig. 2. It will therefore be seen, that the facing will extend along the outer side of the index finger pocket, around the quirk of the thumb and along the inner side of the thumb pocket, the sections of the facing extending from the median line 100 of the said sides, and having their edges sewed or otherwise secured to the respective faces of the index finger and thumb pockets. The facing extending around the quirk of

the thumb pocket reinforces same, so that the index finger and thumb pockets are substantial and are devoid of a seam therebetween or along their outer and inner sides, respectively.

5 The remainder of the glove comprises two symmetrical palm sections 10 having the middle or second finger and third and little finger sections 11 and 12, respectively. The edges of the opposite finger sections 11 and 12 are sewed together, the outer edges of the palm portions 10 being sewed together and the inner edges thereof being sewed to the edges of the blank forming the index finger and the thumb pockets along the edges provided by the cuts 5. The edges of the blank forming the index finger and thumb pockets are also sewed together along the inner and outer edges, respectively, of the index finger 20 and thumb pockets.

10 A knit wrist portion 13 is attached to the lower edges of the extensions 4 and the palm portions 10, this wrist portion yielding to provide a ready passage of the hand there-through and contracting about the wrist of the wearer when the glove is in use, as is customary.

15 The form of glove shown in Fig. 4 is similar to the form shown in Fig. 1, with the exception that the palm portions 10 are each provided with a single finger section 14 for the reception of the second, third and fourth or middle, annular and little fingers.

20 The form of glove shown in Fig. 5 is similar to the form shown in Fig. 1, with the exception that the wrist portion 13 is substituted by a wrist portion 15, so that the glove is in the form of a gauntlet. The extensions of the thumb sections 3, also comprise two parts each, the parts 4^a integral with the thumb sections 3 and the parts 4^b sewed or otherwise attached to the parts 4^a. If, however, it is desired, the parts 4^a and 4^b may be integral as in the former construction.

25 The form of glove shown in Fig. 7 is somewhat similar to the form shown in Fig. 1, the index or fore-finger sections 2 being substituted for the sections 2' for receiving both the fore and middle fingers, the extensions 4 being substituted by enlarged extensions 4' forming a portion of the wrist of the glove, the palm sections 10' having the single finger sections 12 for receiving the 30 annular and little fingers, and opposite wrist sections 16 being provided which are sewed to the edges of the extension 4' and the lower edges of the palm sections 10'.

35 The form of glove shown in Figs. 9 and 10 is also similar to the form shown in Fig. 1, with the exception that one palm section 10 is provided with the finger sections 11, 18 and 19, respectively, for receiving the second, third and fourth fingers, and the 40 other palm section 10 being only provided

with a finger section 19 cooperating with the corresponding finger section of the other palm section to provide the little finger pocket. The middle and annular finger pockets are completed by the respective fourchettes 11' and 18', respectively, as will be apparent and as well understood in the art.

70 In the form shown in Fig. 11, the palm sections 10 are provided with a single finger section 20, the inner edges of the blank forming the index finger pocket being sewed to the edges of the finger sections 20, so as to provide a single pocket for the four fingers.

75 It is desirable to provide a lacing 17 for the form shown in Fig. 7; which lacing is threaded around the wrist portion of the said glove, so that the wrist portion may be contracted about the wrist of the wearer, this lacing being shown in detail in the aforementioned application.

80 From the foregoing, taken in connection with the drawings, it will be apparent that the present invention is applicable to gloves having various numbers and forms of finger pockets; the construction of the index finger and thumb pockets and the facing remaining the same throughout the various forms. The various gloves may also be provided with various forms of wrist portions. It will also be apparent, that the objects aimed at have been attained in a convenient and satisfactory manner, and that this glove is susceptible of numerous alterations or deviations in its details within the scope of the appended claims without departing from the spirit of the invention.

85 Having thus described the invention, what is claimed as new is:—

1. In a glove, a blank doubled longitudinally and bent intermediate its ends to form both sides of the index finger and thumb pockets, the sections of the thumb pocket having extensions projecting toward the wrist.

100 105 110 114 120 125 130

2. In a glove, a blank having oppositely projecting index finger and thumb sections separated by cuts, the thumb sections having extensions, the blank being doubled longitudinally and being bent between the said sections to form both sides of the index finger and thumb pockets, the said extensions projecting toward the wrist.

3. In a glove, palm sections, integral index finger and thumb pockets formed from a blank doubled on its median line and bent intermediate its ends to provide both sides of the said pockets, certain edges of the said blank being sewed together to define the pockets, and the other edges being sewed to the palm sections.

4. In a glove, integral thumb and index finger pockets formed from a blank symmetrical at the sides of its median line and having oppositely projecting index finger

and thumb sections along the median line, separated by cuts terminating short of the median line, the blank being doubled on the median line and being bent between the index finger and thumb sections to provide the quirk, the edges of the blank being secured to the remainder of the glove.

In testimony that I claim the foregoing as my own, I have hereto affixed my signature in the presence of two witnesses.

EDWIN T. BASKIN.
